DIAL CONTROL FOR MULTIPLE GAS COCKS

Edward E. Hodgkin, William W. Wodell, and Henry Lange, Quincy, Ill., assignors to Quincy Stove Manufacturing Co., Quincy, Ill.

Application July 18, 1932, Serial No. 623,163

3 Claims. (Cl. 277—4)

Our invention relates to devices used in the control of gas burners; an object being in our device to provide a single dial control valve for gas burners.

5 We have for our major purpose in this invention to provide a simple, economical, and practical means of controlling gas burners of a gas range, for instance by the control of one dial in its selective adjustments; wherein the same dial may be 10 used for the control of any one of the gas burners one at a time.

We attain the objects of our invention by the mechanism described in the annexed specification recited in the claims and illustrated in the 15 accompanying drawings in which like reference numerals indicate like parts in the several figures.

Referring to the figures:

Figure 1 is a top view of our invention shown in 20 partial section disclosing details of construction thereof.

Figure 2 is a front view of the control dial of our invention showing in dotted lines and in section the operative relation of the control dial 25 with the gear segments on the valves.

Figure 3 is a top view of our invention shown connected with the leads which run to the gas burners.

Figure 4 is a front view of our invention illustrated in Figure 3.

Figure 5 is a complete horizontal half-section of our invention.

Figure 6 is a detail of the operative gear meshing relations of the valve stem gear segments and 35 the control dial gear segments. This detail shows also the stem of the valve.

Referring now in detail to the construction of our invention and the preferred method of operating the same, we provide a housing 1 shaped 40 to define a gas receiving chamber 2 and provided with a gas intake connection 3.

To this housing there is detachably connected a plurality of valve casings 4, 5, 6, and 7. These valve casings are preferably provided with 45 threaded attachments 8, 9, 10, and 11 made integral with the casing.

Operating as a valve in each of these casings a valve stem 12 is provided with one tubular end 13 with an outlet 14 and a valve orifice 15 on one 50 side communicating with the tubular portion of the stem.

On the end of the valve stem opposite the tubular portion there is fixedly secured a gear segment 16 adapted to mesh with and be controlled 55 by a relatively small gear segment 17 of a control

dial 18 supportably mounted on a shaft 19 and both slidably movable and freely rotatable thereon.

This control dial is retained on shaft 19 by a cap screw 20 while a compression spring 21 mounted on shaft 19 between dial 18 and housing 1 is adapted to normally hold dial 18 out of engagement with gear segments 16 on valve stems 12 of the respective valves.

When it is desired to light one of the burners 10 22, 23, 24, and 25 then the valve connected with that burner will be manipulated by slidably pushing in on dial 18 against spring 21 until gear segment 17 slides into mesh with gear segment 16 controlling the valve which releases gas to that 15 burner. When dial 18 is thus in mesh with the gear segment 16 it is then held in place while rotating the dial to the extent necessary to bring orifice 15 of that stem 12 into registry with the housing gas outlet passage 26 for the valve being 20 used, thus opening the way for the gas to move from receiving chamber 2 to the burner to be lighted.

When the gas enters orifice 15 from chamber 2 through passage 26 it will leave the tubular end 25 14 of valve member 12 on its way to the gas burner.

It will be observed that by means of our invention any desired adjustment may be made in the size of the blaze in the burner by selectively adjusting the position of rotation of orifice 15 in stem 12; thus regulating the amount of gas which may pass through the valve from outlet passage 26 communicating with gas receiving chamber 2.

Thus it will be observed that any one of the burners may be lighted and suitably adjusted, one at a time, by turning gear segment 17 of dial 18 around to the gear segment 16 on the valve stem to be adjusted and slidably pushing in on dial 18 to bring gear 17 into mesh with gear segment 16 of the desired valve so as to rotate the valve connected therewith by turning dial 18 rotatably on shaft 19. This will release the gas for the desired burner from receiving chamber 2 which gets its supply of gas through a feed pipe 27.

Valves 4, 5, 6, and 7 are connected with gas distributing pipes 28, 29, 30, and 31 which carry the gas to the burners 22, 23, 24, and 25.

It is conceivable that instead of using distributing pipes 28, 29, 30, and 31 a casting with distributing channels may be used within the spirit of our invention while it is evident that other minor changes in the construction of our 55

device may be made without departing from the scope of our invention.

The salient structural features of our invention having been pointed out and described what we claim is:

1. A single dial control valve for gas burners comprising a gas receiving housing provided with a plurality of valve cylinders, a plurality of communicatively connected spigot valves rotatably 10 registering in said valve cylinders and disposed with the cylinders in circumferential alignment about the housing, an integral valve stem for each of said valves and a gear segment secured to the free end of each of said valve stems, a 15 control dial having a peripheral gear segment adapted to be selectively rotated and slidably moved into mesh respectively with said gear segments for the selective control thereof, a shaft for the support of said dial and a spring for 20 resiliently holding said dial out of engagement with said valves except when pressure is applied against the spring.
2. A gas control appliance comprising a housing adapted to be connected with a source of gas 25 supply and shaped to define a gas receiving chamber therein; a plurality of valves for selectively releasing gas from said receiving chamber in the housing out to gas burners adapted to be connected with said valves, a dial supporting 30 shaft and a control dial provided with a peripheral gear segment and freely rotatable and resiliently supported on said shaft; said valves

being each provided with a gear segment and an integral valve stem for the support thereof and each of said gear segments being adapted to selectively mesh, one at a time, with said gear segment of said dial for the optional control of said valves by the selective adjustment and rotation of said dial.

3. A dial control for multiple gas cocks comprising a housing for receiving gas from a source of fuel supply, a plurality of gas outlet control 10 valve casings spaced from and communicatively connected with said housing in concentric alignment about the housing, a valve for each of said valve casings provided with a control stem and a gear segment at the terminal thereof, a control 15 dial having an internal peripheral flange provided with a relatively small number of internal gear teeth adapted to selectively mesh with the gear teeth of said valve stem terminals for the rotatable adjustment of said valves communicating with said housing; a fixed shaft supported by said housing, a compression spring mounted on the shaft and said dial being freely rotatable on said shaft and mounted so as to compress said spring when in engagement with said gear 20 segments on said valve stems and adapted to be automatically and slidably moved by said spring out of engagement with said valve gear segments when hand control is released therefrom.
